UNITED STATES PATENT OFFICE

2,052,217

ALL WEATHER STADIUM

Jules H. de Sibour and George P. Marshall,
Washington, D. C.

Application June 20, 1933, Serial No. 676,755

2 Claims. (Cl. 189—1)

This invention relates to certain new and useful improvements in an all weather stadium, the object being to provide a stadium with a sectional roof which can be moved into such a position that the field portion of the stadium will be exposed or into such a position as to completely inclose the entire stadium so as to protect the playing field as well as the spectators from the weather, the construction being such that the desired height is maintained in order to allow foot ball to be played within the stadium.

Another object of our invention is to provide a stadium in which the tiers of seats are so arranged that the seating capacity is greatly increased and yet the tiers of seats are maintained in proximity to the playing field.

Another object of the invention is to provide a stadium which can be used for any and all sports with the exception of base ball, means being provided for forming a swimming pool in the playing field, an ice rink and a track and by placing a ring within the center of the field, boxing bouts can be held within the stadium so that all of the spectators will have a clear view of the ring.

Another object of the invention is to sub-divide the grandstand into units of approximately one hundred feet length, each unit being provided with the necessary ramps and stairways and the other accommodations for spectators, yet maintaining each unit in communication with the other units.

A still further object of the invention is to provide a rolling roof for the field, preferably formed of eight panels constructed of frames, four to each side of the longitudinal center, which panels are mounted on rollers on the fixed inclined roof of the stadium, each section thus formed being provided with means, such as an electric motor, for moving each section independent of the other whereby these roof sections can be adjusted into various positions so as to completely inclose the stadium or partly inclose the same and when moved into position over the fixed section of the roof will expose the entire playing field so that an open air stadium is formed, and when moved into position to inclose the stadium, the entire field will be covered, means being provided for heating the stadium in any suitable manner, such as arranging pipes under the seats or in various ways, whereby the stadium can be used for playing ice hockey and the like and yet the spectators will not suffer from the cold.

Another and further object of the invention is to provide a stadium which is preferably formed of steel and concrete of the desired size, with the

seats arranged in such a manner that all the seats have a clear view of the playing field.

Other and further objects and advantages of the invention will be hereinafter set forth and the novel features thereof defined in the appended claims.

In the drawings,

Figure 1 is a horizontal section taken through a stadium constructed in accordance with the invention, in a plane below the lower tier of seats showing the various rooms and exits to and from the field for the players, bathers and the like, means being provided to form accommodations at one end for women and at the other end for men and in the center for players and officials;

Figure 2 is a horizontal section showing the lower tiers of seats at one end and the upper tiers of seats at the other end with the various accommodations and concessions for the spectators;

Figure 3 is a detail enlarged plan view of one of the units of the lower tiers of seats forming one of the sections of the grandstand;

Figure 4 is a transverse section through half the stadium showing the roof in position to inclose the field and the field converted into a swimming pool with a central island with bridges leading to the various dressing rooms as shown in Figure 1;

Figure 5 is a detail transverse section through part of one of the roof frames showing the manner of mounting the frame and propelling the same so as to move it back and forth on the fixed section of the roof;

Figure 6 is a sectional view through a portion of the fixed roof structure and one of the movable roof frames with its driving means for the rollers supporting the same;

Figure 7 is a vertical section through a portion of the fixed roof section with two of the abutting movable roof frames showing the gutter between the two sections in order to form a weather tight joint between the sections as they move independent of one another;

Figure 8 is a detail section showing the construction of the meeting ends of the various sliding roof frames with the gutter and weather stripping in position to form a tight joint when these two sections are moved into contact with one another; and

Figure 9 is a detail plan view of a portion of one of the roof frames with its glass enclosure removed showing the electric motor and its

30

driving means for moving the frame back and forth on the fixed roof.

In the embodiment of the invention herein shown the stadium is preferably formed of steel 5 and concrete and comprises a suitable annular base above which is arranged a lower tier of seats 1 and an upper tier of seats 2 and a fixed roof structure 3, each tier of seats being formed in units with its own ramps and staircases, these 10 tiers being in communication with each other by corridors in order to allow the spectators to pass from one section to another.

Each unit is provided with suitable aisles and 15 corridors with concession areas and toilets. This provides accommodations for the spectators and means for allowing the spectators to reach and leave their seats quickly yet maintain the tiers of seats in such a position that the spectators will have a clear view of the field.

20 These tiers of seats and a fixed roof structure surround a central playing field of such a size that a regulation foot ball field with a space surrounding the same is formed which can be converted into a track and the field is so constructed 25 that a swimming pool 4 can be formed with a central island 5 having bridges 6 leading thereto which extend from suitable passageways leading from dressing rooms disposed below the lower tiers of seats as clearly shown in Figure 1 of the 30 drawings which is also provided with sufficient space to form club rooms and dressing rooms for the players.

The central island 5 formed in the playing 35 field when the field is converted into a swimming pool is covered with sand and this island is arranged above a suitable tank 7 shown in Figure 4 which is capable of being converted into an ice rink.

The construction thus far described discloses 40 an open air stadium with two tiers of seats surrounding the playing field divided into units, each unit having its own ramps and stairways, and facilities for accommodating the spectators with its fixed roof section protecting the tiers of 45 seats.

This roof section is formed of sufficient strength by suitable beams and trusses to support the sliding roof sections as will be herein-after fully described in order to allow the stadium to be completely closed to protect the playing field from rain and snow and to allow the stadium to be heated and maintained at the proper temperature whereby the spectators will not be subjected to discomfort irrespective of the 55 atmospheric conditions on the outside and by using the conventional illuminating systems the stadium can be used at night as well as day.

The movable roof as shown, is formed of eight sections, four to each side of the longitudinal 60 center of the field, each section comprising a glazed panel composed of a suitable frame 8, the description of one being sufficient for all. Each roof frame is provided with rollers 9 mounted on suitable tracks 10 arranged on the fixed roof 65 3, these sections being mounted to move independent of one another and to move back and forth by independent propelling means.

The roof frames are inclosed in glass by any suitable skylight structures 11 and the adjacent 70 roof sections carry cooperating gutter members 12 and 13, which slide one within the other, one section being provided with a suitable packing, such as leather, to form a tight joint between the adjacent sections as these sections move independent with one another.

The opposing ends of the roof sections or panels which meet at the longitudinal center of the stadium are provided with cooperating gutter members 14 and 15 which are likewise provided with suitable packing material to form a tight joint when the various sections are brought into contact with one another by moving the rolling roof sections outwardly to inclose the field. 5

The rear ends of the roof sections are counterbalanced as shown at 16 by forming these ends 10 of masonry to offset the weight of heavy snow on the unsupported ends of the panels and a bumper 17 is provided to cooperate with these sections as the roof sections are moved from over the field. 15

Disposed within the frame work forming the panel of each roof section is an electric motor 18 provided with a gear reduction box 19 from which extends a drive shaft carrying a driving gear 20 which meshes with a pinion 21 on a driven shaft 22 and through suitable driving connections, such as gears 23, the propeller shaft 24 is driven which is provided with wheels 25 traveling on the tracks 10 so as to propel the roof panels back and forth on the fixed roof in order to inclose the stadium 25 or to move the roof sections from over the playing field.

The electric motor is provided with an automatic brake 26 for holding the roof panels in any position desired and it is, of course, understood that 30 a suitable flexible conduit, which can be mounted on a drum as shown at 27, can be employed for supplying the desired energy to the electric motor so as to move the panels and while we have shown certain details of construction of driving 35 these panels forming the sectional roof, it is, of course, understood that certain changes can be made without departing from the spirit of our invention.

It is, of course, understood that the particular 40 manner of mounting the panels on tracks can be departed from without departing from the spirit of the invention, as the invention consists in constructing an all weather stadium by movably mounting on the fixed roof of the stadium a plurality of glazed panels formed of frames movably mounted independent of one another and independently propelled so that they can be adjusted into various positions so as to completely or partly close the stadium and therefore the right is reserved to change these details of construction without departing from the spirit of the invention 45 as defined in the claims.

From the foregoing description it will be seen that we have provided a stadium comprising a 55 central playing field surrounded by a steel and concrete structure composed of two tiers of seats, the lower tier extending outwardly beyond the upper tier with the roof structure covering both tiers and extending outwardly beyond the lower 60 tier of seats, said roof structure being of such a height and so formed that it provides a rigid support for a plurality of glazed panels which are movably mounted thereon and so constructed that these panels interlock with one another to form 65 a weather tight joint between the same whereby these panels can be moved upwardly and outwardly so as to contact with one another to completely inclose the playing field in order to protect it from snow and rain, thereby providing a convertible stadium which in good weather is an open air stadium and in bad weather can be converted into a closed structure.

In the disclosure the fixed roof structure covering the superposed rows of tiers is only half. 70

covered by any suitable roof covering as the movable glazed panel roof sections which are slidably mounted on this roof structure form a covering for the uncovered portion of the fixed roof section irrespective of the position the movable panels are in for it will be noted that these panels are of such a size that when they are extended to cover the playing field, there remains a sufficient portion of these panels over the fixed roof structure to cover that portion and protect it from the rain and snow and when the panels are moved inwardly so as to expose the playing field, this unexposed portion of the fixed roof structure is also covered by the panels.

This enables the driving mechanism to be mounted on tracks supported by the roof structure and as the movable panels carry electric motors with driving wheels which are driven through a plurality of gears, these glazed roof panels can be moved back and forth very rapidly and are counter-balanced when in extended position.

What we claim is:

1. An all weather stadium comprising a central playing field free from aerial obstructions

and surrounded by tiers of seats, a fixed roof structure covering said tiers of seats, a plurality of roof panels slidably mounted on said fixed roof structure and wholly supported thereby and adapted to be moved outwardly to completely cover the playing field and interlocking members slidably contacting each other between said roof panels and slidably interlocking members between the ends of the opposite panels when extended to the center of the playing field. 10

2. An all weather stadium comprising a central playing field free from aerial obstructions and surrounded by tiers of seats, a fixed roof structure covering said tiers of seats, a plurality of roof panels slidably mounted on said fixed roof structure and wholly supported thereby, means for moving said panels outwardly for completely covering the playing field, and each panel having at its sides gutter members slidably interlocking, and the ends of each panel having gutter members slidably interlocking with the opposite panel when extended to the center of the field. 15 20

JULES H. DE SIBOUR.
